(74) Attorney, Agent, or Firm — Woods Oviatt Gilman
LLP; Ronald J. Kisicki, Esq.(57) **CLAIM**

The ornamental design for the electric strike, as shown and described.

DESCRIPTION

FIG. 1 is a front right perspective view of an electric strike showing our new design;

FIG. 2 is a top view thereof;

FIG. 3 is a front view thereof;

FIG. 4 is a bottom view thereof;

FIG. 5 is a back view thereof;

FIG. 6 is a left side view thereof; and,

FIG. 7 is a right side view thereof.

The broken lines illustrate unclaimed portions and form no part of the claimed design.
